[57] CLAIM

The ornamental design for a portable air bubble mat, as
shown and described.

DESCRIPTION

FIG. 1 is a front perspective view of a portable air
bubble mat showing my new design;
FIG. 2 is a perspective view from below of the portable
air bubble mat illustrated in FIG. 1;
FIG. 3 is a left side elevational view thereof, the right
side being a mirror image thereof;
FIG. 4 is a top plan view thereof; and
FIG. 5 is a rear elevational view of the portable air
bubble mat shown in FIG. 1.
